DROP-FORGED ROTOR

Curt F. Reis, Chicago, Ill.

Application January 10, 1938, Serial No. 184,206

2 Claims. (Cl. 171—209)

This invention relates to improvements in magneto rotor construction, and more particularly to an improved low cost construction of rotor for magneto-electric machines of so-called 5 rotating field type.

The present invention has as its primary objective, the production of a more rugged, dependable, low-cost rotor for magnetos of the type referred to, characterized by a drop-forged rotor 10 frame construction, and an assembly not necessarily involving the use of casting operations of any kind, with the possible exception that the permanent magnets, pole pieces or magnet bars may be initially formed by casting prior to assembly of the elements of the rotor.

Yet another object of the invention is attained in the production of a rotor for magnetos of rotating field type, which may be formed to include a frame structure of drop-forged metal, 20 and which is characterized by a minimization of length or axial dimension, and serves to dispense with magnetic bridging plates, end plates, or comparable elements often heretofore employed in rotors for rotating-field type magnetos.

Yet another object of the invention is attained 25 in an improved method of forming certain of the parts of a rotor for a machine of the type referred to, and which effects certain assembly economies and improves the integration of the 30 structure, by drop-forging a complete shaft element together with end plates formed integrally therewith in a single forging operation, and optionally as a part of the unitary forged structure, an intermediate structural support or bridge for the pole-shoe members.

The foregoing and numerous other objects will 35 appear as the description proceeds, when considered in connection with the accompanying drawing of a presently preferred structural embodiment of the invention. In the drawing:

Fig. 1 is a side elevation of a complete rotor 40 formed in accordance with the method to be described, and embodying a structure resulting from the invention; Fig. 2 is a sectional elevation 45 of the device as it would appear when viewed along line 2—2 of Fig. 1; Fig. 3 is an axial section of the rotor of Fig. 1, as would appear when viewed along line 3—3 of Fig. 2; Fig. 4 is a transverse sectional elevation taken along line 4—4 of Fig. 1, and Fig. 5 is a section of the device as 50 viewed along line 5—5 of Fig. 2, except that, for clearness, the bar magnets or pole pieces are shown in elevation.

Referring now by characters of reference to 55 the drawing, the rotor frame, which in the pres-

ent example may be said to embody all of the elements of the completed rotor but for the pole pieces or magnets together with pole shoes and assembly elements such as rivets, includes as an integral drop-forged structure a shaft portion including a drive end 10 provided with a reduced threaded extremity 11 for the reception of a gear- or coupling-holding nut or the like (not shown); the shaft portion 10 is tapered between the part 12 of normal diameter and the threaded end 11, so as to form a tapered fit for the reception of the coupling member in case an impulse coupling is utilized. Intermediate shaft portions 13, also parts of the integrally formed drop forged structure, lie at opposite sides of a 15 central spacer 15, this element serving as a structural bridge between the pole shoes, as will hereinafter appear. The metal of the forging is diametrically extended to form a pair of end plate members, one thereof appearing at 16, near the 20 driving end, and the other plate portion 17 being located near the opposite end of the rotor. Just beyond the plate 17 is a relatively enlarged shaft portion 18. Either the portion 18 or a free end 19 therebeyond, may be used, according to 25 frame design of the machine, as a journaled portion for this end of the shaft. The portion 19 may also at the time of or after drop-forging the frame, be formed or shaped to constitute a 30 breaker cam, if so desired.

In the assembly presently described by way of 35 illustration, the pole pieces, being of bar form and preferably circular in section, are four in number, and are arranged transversely of the axis of the rotor, being arranged in pairs at opposite sides 40 of the axis. The magnet bars are indicated at 20, being suitably arranged with respect to their polarity, as well understood. It is my great preference to employ for the magnet bars, an alloy characterized by high coercive force and retentivity, among the materials particularly suitable for the purpose being certain of the alloys known as Alnico steel.

Proceeding now to a description of the pole 45 shoes, in the present example two thereof are utilized, and are diametrically and peripherally disposed in assembly, being indicated at 22 and 23. Each pole shoe is provided with a number of recesses or sockets 25 corresponding to the 50 number of magnet bars or pole pieces employed. Each of the pole shoes is further of laminated construction as will appear, the laminations being compressed prior to assembly of the shoes into the rotor, and the assembly constituting each shoe, drilled say in a multiple drill, to pro- 55

vide the requisite number of sockets or recesses, each conforming in its internal diameter fairly closely to the external diameter of the end of the associated bar magnet, whereby there results 5 a close or press fit between the shoes and the ends of the magnets so as to insure a uniformly good flux path between these elements.

Suitable temporary holding means (not shown) being provided for retaining the shoes in assembly 10 over the ends of the pole pieces, this sub-assembly is then definitely positioned within the drop-forged frame as described. Permanent assembly is effected, preferably by drilling through the shoes and the end plate portions 16 and 17 to 15 provide passages or bores for assembly rivets 30. With the parts thus far referred to suitably held in a jig or the like, the rivets 30 are inserted and their opposite ends upset or headed into countersunk recesses 31 in the end portions 16 and 17 20 respectively.

In the form of rotor shown and embodying cylindrical magnet bars or pole pieces 20 of substantial size, it has been found desirable to provide the spacer 15 as a structural bridge for the 25 intermediate portions of the shoe assemblies 23. However, in a rotor for a smaller machine or one requiring only magnet bars of smaller size, it is 30 entirely feasible to construct the rotor frame by drop-forging, and to omit the intermediate spacer element 15. In the example illustrated utilizing the element 15, the pole shoes are each desirably provided with a rectangular or other suitable 35 form of recesses 35 which provides for a rigid interfitting engagement between the shoes and the center support. This recess may be provided by utilizing the requisite number of laminations or 40 punchings in the central portion of each of the shoes, of a suitably reduced width, or so notched as to accommodate the ends of the center support 15. This provides a definite saddled relation 45 between the shoes and their support, and besides making for structural rigidity of the rotor assembly, the support 15 is so selected as to length or dimension transversely of the rotor axis, that it receives and takes any compression stresses during and after assembly and thus relieves the 50 magnet bars of any strains resulting from endwise compression thereof. This is highly desirable in the case of pole pieces formed of certain alloys characterized by a relatively coarse crystalline 55 structure, wherein for both structural and magnetic reasons it is desirable to obviate any substantial compression stresses.

In case the rotor is formed according to a 55 design in which the center element 15 is omitted, it is a preference so to regulate the length of the bars with respect to the distance between the bottoms of opposed bar sockets, that the end plates, such as 16 and 17, receive any compression 60 stresses incident to the assembly.

By way of reviewing the major steps involved in the construction of the rotor or rotors herein described, it may be noted that the rotor frame, including as an integral structure, the portions 65 12, 13, 15, 16, 17, 18 and 19, is or may be formed, preferably of a relatively non-magnetic metal, such as a brass or other suitable non-magnetic alloys susceptible of formation by drop-forging, the elements noted being formed up by further 70 preference, in a single drop-forging operation, the stock from which the forging is formed being heated to the extent, according to the alloy utilized, necessary to enable it to be drop-forged. The forging impact is preferably in a direction 75 normal to the axis of the finished rotor. Follow-

ing formation and any necessary machining, for example, cutting the threads on the shaft end 11, or any machining desired for shaping a breaker cam on the opposite end of the shaft, the pole shoes 22 and 23 are drilled or otherwise recessed 5 to receive the ends of the magnet bars, and are then assembled to the bars and held in a suitable jig prior to and during assembly into the drop-forged rotor frame. Final assembly is completed, as heretofore briefly mentioned, by secure attachment through the use of rivets 30 or an equivalent thereof. Either before assembly of the shoes and bars to the frame, or thereafter, any external machine operations may be effected on the exposed portions of the rotor. 15

As will appear from the drawing, it is my preference to extend at least one, say the central rivet 30 of each group, through the bridge or spacer element 15. This may be done either by providing recesses or openings, shown at 34, in 20 the end portions of the spacer element. This arrangement offers a distinct structural advantage in an increased torsional rigidity of the cage or frame, and hence of the rotor itself, the arrangement being particularly desirable in the 25 event an impulse coupling is utilized for connecting the magneto to the associated engine.

The present disclosure has included no detailed or specific description of the remaining parts of the magneto, as they are or may be of any of a 30 number of suitable types and arrangement. As an example of a magneto frame, winding, distributor, breaker assembly, etc., with which a rotor of the present type is adapted for use, attention is directed to my copending application Serial 35 No. 184,207, filed January 10, 1938. The magnetic and electrical circuits of the completed machine embodying the rotor of the present invention may, however, be conventional, and will readily be understood by those skilled in the art. 40

The production of a rotor cage or frame by drop-forging has, of itself, been known and utilized heretofore, having been disclosed and made the subject of claims in U. S. Letters Patent No. 2,059,745, issued to this applicant November 3, 45 1936. However, in the earlier design, the magnet bars were positioned in their final relation and while so positioned, the body of holding metal constituting the cage or frame, was drop-forged about the magnets. However, with the 50 advent of magnetic alloys characterized by improved magnetic properties, but which are, by reason of internal metallic structure, sensitive to compressive stresses, there has arisen a need for a drop-forged rotor construction in which the 55 frame, although forged, is initially formed, and the magnet bars assembled into the frame after forging. The method and structure thus outlined by the present disclosure is accordingly the reverse of, and hence fully distinguishable from the 60 method or process described and claimed in Patent 2,059,745.

It will have appeared from the foregoing description and the accompanying drawing, that magneto rotors formed in accordance with the 65 present principles, fully attain each of the several objects hereinabove mentioned, as well as in many others, and that the invention has resulted in a magneto rotor for machines of rotating field type, constituting a distinct advance in 70 the art.

Although the invention has been described by making detailed reference to a specific embodiment of the invention selected for purposes of patent disclosure, this description is to be under- 75

stood entirely in a descriptive sense, and not with any limitations in meaning, except such as may be imposed by the claims hereunto appended.

5. I claim as my invention:

1. In a rotor structure for magnetos of rotating field type, an assembly of permanent magnets of bar form disposed parallel to each other, and substantially transversely of the rotor axis, a pole shoe overlying each end of the magnet assembly, a drop-forged cage or frame for the rotor, formed of a non-magnetic metal and including a stub shaft portion for each end of the rotor, an intermediate shaft portion, a pair of end plates of substantially circular form spaced from each other and located inwardly of the stub shaft portions, a center spacer bar substantially normal to the intermediate shaft portion and between the end plates, the bar magnets and pole shoes being assembled into the cage between the end plates, with the shoes in abutting engagement to the center bar, and elongate holding elements extending through the shoes and end plates and serving to secure the plates and shoes into 25 the cage.

2. In a rotor structure for magnetos of rotating field type, an assembly of permanent magnets of bar form disposed parallel to each other and substantially transversely of the rotor axis, a pole shoe overlying each end of the magnet assembly, a drop forged cage or frame for the rotor, formed of a non-magnetic metal and including a stub shaft portion for each end of the rotor, an intermediate shaft portion, a pair of end plates of substantially circular form spaced from each other and located inwardly of the stub shaft portions, a center spacer bar substantially normal to the intermediate shaft portion and between the end plates, the bar magnets and pole shoes being assembled into the cage between the end plates, 10 with the shoes in engagement with the center bar, elongate holding elements extending through the shoes and end plates whereby to secure the plates and shoes into the cage, the pole shoes being of laminated construction and recessed from their inner faces so as interfittingly to receive the ends of the center spacer bar and the ends of the bar magnets. 15 20
